No. 36,529.

Patented August 25, 1903.

UNITED STATES PATENT OFFICE.

SZYMON BALINSKI, OF BOSTON, MASSACHUSETTS.

DESIGN FOR A PICTURE-FRAME.

SPECIFICATION forming part of Design No. 36,529, dated August 25, 1903.

Application filed July 8, 1903. Serial No. 164,756. Term of patent 7 years.

To all whom it may concern:

Be it known that I, SZYMON BALINSKI, a subject of the Emperor of Austria-Hungary, residing at Boston, county of Suffolk, Commonwealth of Massachusetts, have invented a new, original, and ornamental Design for Picture-Frames, of which the following is a specification.

The figure is a view of a frame, showing my new design.

What I claim as new, and desire to secure by Letters Patent, is—

The ornamental design for a picture-frame, as shown.

In testimony whereof I affix my signature in presence of two witnesses.

SZYMON BALINSKI.
